COOKING UNIT

Harald Finnstrand, Pelham, N.Y., assignor to Homestrand Incorporated, Larchmont, N.Y., a corporation of New York

Filed Jan. 10, 1966, Ser. No. 560

Term of patent 14 years

(Cl. D81—25)

FIG. 1 is a plan view of a cooking unit in accordance with my new design;

FIG. 2 is a front elevational view of the FIG. 1 unit and of the FIG. 5 unit;

FIG. 3 is a side elevational view of the FIG. 1 unit;

FIG. 4 is a sectional view of the FIG. 1 unit, taken along line 4—4 of FIG. 1;

FIG. 5 is a plan view of another embodiment of a cooking unit in accordance with my new design;

FIG. 6 is a side elevational view of the FIG. 5 unit; and

FIG. 7 is a sectional view of the FIG. 5 unit, taken along line 7—7 of FIG. 5.

The dominant features of my design reside in those portions shown in full lines in the drawings.

I claim:

The ornamental design for a cooking unit, substantially as shown and described.
